UNITED STATES PATENT OFFICE

ALBERT B. RANDALL, OF WHITESTONE, NEW YORK

HINGED FASTENING DEVICE

Application filed January 9, 1930. Serial No. 419,616.

My invention relates broadly to hinged fastening devices for papers and the like and more particularly to a construction of hinged fastening device for attaching a sheet-like member to a supporting surface in such manner that both sides of the sheet-like member may be readily inspected.

One of the objects of my invention is to provide a construction of hinged fastening device having means for detachably receiving a sheet-like member in predetermined position with respect to a supporting sheet.

Another object of my invention is to provide a construction of hinged fastening device particularly adapted for use in stamp albums for detachably mounting covers or stamped envelopes in an album in predetermined position.

Still another object of my invention is to provide a construction of hinged fastening device for stamped envelopes for use by collectors in mounting stamped envelopes within a stamp album, wherein means are provided for detachably mounting exhibit envelopes in predetermined position with respect to the pages of the album, with means for maintaining the exhibit envelopes in substantial adherence to the pages of the album as the album is leafed.

A further object of my invention is to provide a construction of hinged fastening device for use in mounting envelopes in stamp albums, wherein means are provided for preventing creasing of the envelopes under grip of the detachable means, while permitting ready inspection of both sides of the envelope.

Other and further objects of my invention reside in the construction of hinged fastening device, as set forth more fully in the specification hereinafter following by reference to the accompanying drawings in which:

Figure 1 is a fragmentary perspective view of a stamp album showing my improved fastening and attachment device in position therein, the fastening device being shown in a position for mounting a specimen envelope; Fig. 2 is a detailed front elevation of fastening device illustrated in Fig. 1 and showing a fragment of the envelope in position in the fastening device; Fig. 3 is a detailed perspective view of the fastener viewing the same from the front; Fig. 4 is a perspective view of the fastener viewing the same from the rear or attachment surface thereof; Fig. 5 is a detailed front elevation of a modified form of improved fastener clip; Fig. 6 is a detailed perspective view showing the securing clip of my invention as illustrated in Fig. 5 about to be positioned within the attachable fastening device; Fig. 7 is a detailed perspective view of the fastener shown in Fig. 5; Fig. 8 is a detailed front elevation of a further modified form of hinged fastening device embodying my invention; Fig. 9 is a perspective view of the parts of the hinged fastening device shown in Fig. 8 where the clip is about to be assembled within the hinged attachment member; Fig. 10 is a perspective view of a modified form of attachment device illustrated in Fig. 8 as it is finally assembled; Fig. 11 is a front elevation of a still further modified form of fastening device showing the clip provided with a spring member for maintaining the cover or envelope which is mounted in the stamp album by means of the device in close adherence to the surface of the page with respect to which the envelope is mounted; Fig. 12 is an enlarged cross-sectional view taken on line 12-12 through the fastening device construction of Fig. 11; Fig. 13 illustrates the form of fastening device shown in Figs. 8, 9 and 10 and having guard means enveloping the parts of the clip for preventing creasing of the exhibit envelope; Fig. 14 is a cross sectional view taken through the guard means on line 14-14 of Fig. 13; and Fig. 15 is a perspective view of each of the guard means illustrated in Figs. 13 and 14.

With the increasing use of air mail envelopes there has come a demand by stamp collectors for means for properly preserving specimens of exhibit air mail envelopes. The usual method of mounting stamps in stamp albums by means of a gummed paper hinge has been found to be impracticable for the mounting of air mail envelopes which are known to stamp collectors as "covers" or an "entire". The single paper hinge ordinarily employed in the mounting of stamps has not

been practicable for the mounting of entire envelopes due to the comparative mass of the envelope with respect to the stamp which is usually mounted upon a paper hinge. When a plurality of paper hinges are used for mounting an "entire" difficulty arises in the proper alignment of the several paper hinges and buckling and tearing of the hinge often results under the continued movement 10 of the envelope as the pages of the album are leafed.

My invention provides means for mounting the entire air mail envelope with respect to the pages of a stamp album in a manner which facilitates the quick and easy inspection 15 of both sides of the envelope for observing the cancellations appearing on one side of the envelope and the air mail stamps and post office inscriptions appearing on the front 20 of the envelope. I provide a construction of hinged fastening device having sufficient rigidity to properly position an exhibit envelope with respect to the page of the stamp album. I provide means for readily attaching the 25 fastener to the page of a stamp album in a manner which facilitates the inspection of both sides of the envelope, with spring means for maintaining the envelope in close adherence to the page of the stamp album on which 30 the envelope is mounted so that as the pages of the album are turned the tendency of the envelopes to swing away from the position with respect to which they are mounted is substantially eliminated. I also provide protective covers on the portions of the fastening 35 clip by which the creasing of the exhibit envelope is avoided.

Referring to the drawings in detail, reference character 1 designates a form of stamp 40 album used by a collector for mounting the exhibit stamps. I have illustrated in plan view the page of a stamp album on which a "cover," an envelope or, as a postmarked envelope specimen is known among stamp collectors, an "entire" 2 is mounted hingedly. 45 The fastening means is illustrated as comprising two parts, part 3 of which is secured to the page of the stamp album and part 4 of which is arranged to engage the envelope 2.

50 As shown more clearly in Fig. 2 the portion 4 comprises a length of resilient wire looped upon itself at 5 in a position central with respect to the portion 3 of the fastening device, the loop portions of the resilient wire 55 4 being adapted to engage opposite sides of the envelope 2 for maintaining the envelope in position. The ends of the resilient wire 4 are shown at 6 and 7 projecting between the folded parts of the securing portion 3, which 60 securing portion 3 as shown more clearly in Figs. 3 and 4 is formed from a flat sheet substantially circular in contour and folded diametrically to enclose the inwardly projecting portions 6 and 7 of the resilient wire 4. The 65 folded parts of the securing portion 3 are

glued together, leaving the resilient wire 4 free to move through substantially an angle of 180 degrees about the securing portion 3 as an axis. One side of the securing portion 3 is covered by a glue represented by the stippling illustrated at 8 in Fig. 4 by which the hinged fastening device may be readily attached to the page of the stamp album in a position wherein loop portions 5 of the resilient wire are free to receive the upper edge 70 of the envelope 2 enabling the envelope to be raised from the page for the purpose of inspecting opposite sides thereof. 75

In Figs. 5, 6 and 7 I have shown a modified form of fastening device wherein the securing portion 10 of the fastening device which engages the page of the album shown at 1 has a central diametrical extending slot 9 formed therein. A resilient wire member is illustrated at 11 for forming the two adjacent loops with ends 12 and 14 projecting therefrom, the parts of the resilient wire 11 being adapted to engage opposite sides of the envelope 2. 80 85

The manner of assembling the modified form of hinged fastening device is shown more clearly in Fig. 6 where the resilient wire member 11 is passed through the central diametrically extending slot with the projecting portions 12 and 14 fitted in the diametrical fold 15 of the securing portion 10. The inner faces of the securing means 10 are united by suitable glue or mucilage forming when folded a semi-circular member which is readily attachable to the page of the album 1. 90 The resilient wire 11 is free to revolve through an angle of substantially 180 degrees enabling the envelope carried thereby to be reversed in position in the album, thus allowing inspection of both sides of the envelope. 95 The resilient wire 11 is looped centrally as indicated at 11a, thus providing the two looped portions which engage opposite sides of the envelope. 100 105

In Figs. 8, 9 and 10 a further modified form of mounting clip has been shown. The tab indicated at 16 is formed from a circular sheet of material which is folded diametrically, the sheet of material being apertured at 17 and 18 on either side of a tongue 19 which is cut from the material of the circular sheet 16. The fact that the tongue 19 is severed from the material of the tab 16 enables the parts of the clip device to be inserted through the tab and suspended with 110 respect to the sheet to which the hinged fastening device is attached. The clip device is shown as comprising depending resilient jaws 20 and 21, which extend through the central slot in the tab 16 and engage opposite sides of the envelope 2. A bar member 22 extending diametrically of the tab 16 is welded or otherwise secured to the upper portion 23 of the spring clip for supporting 115 the spring clip in position for angular move- 120 125 130

ment with respect to the tab 16 and the surface 1 on which the tab is mounted. Beneath the upper portion 23 of the spring clip, as shown in Figs. 11—12, I secure the resilient member 24 which extends in the form of a spring finger to a position 25 bearing upon the tab 16 when the tab is folded and affixed by glue or mucilage to the surface 1. The spring 24 tends to constantly urge the jaws 20 and 21 which extend from the portion 23 of the spring clip in a counter-clockwise direction as viewed in Fig. 12 or to a position in alignment with the plane of the tab 16. The spring device 24 prevents an undesired movement of the envelopes when in mounted position at the time that the pages of the album on which the envelopes are mounted are turned. The spring device 24 tends to maintain the envelope or cover 2 in substantial adherence with the surface of the supporting sheet 1 regardless of the movement of sheet 1. Any tendency of the envelope 2 to swing to a position 2a as shown in dotted lines in Fig. 12, where the spring jaws 20a and 21a are also illustrated in dotted outline, is resisted by the action of spring 25 which is moved to dotted line position 25a. Movement of envelope 2a away from the mounting sheet 1 is resisted and the envelope restored to proper position, thereby preventing injury to the envelope.

In the case of rare specimens which it is desired to preserve, I further protect the cover or envelope against creasing under the action of the resilient jaws 20 and 21 by means of the enveloping covers 26 and 27, as shown in Figs. 13, 14, and 15. The enveloping covers are made of celluloid or other material and are formed in the shape of channels having inwardly directed guide jaws 26a and 26b and 27a and 27b as shown. To facilitate the attachment of the envelope covers over the jaws 20 and 21, I provide finger grips 26c and 27c, respectively. The finger grips are utilized in slipping the enveloping covers over the spring jaws to prevent contacting of the jaws directly with the envelope or cover 2 which may be a very rare specimen and not replaceable. I may construct the enveloping covers of a single sheet of material properly apertured to permit the insertion thereof upon the spring jaws.

The fastening device of my invention may be employed for a variety of purposes, such as the mounting of advertising cards, the mounting of restaurant menus, and the attachment of advertising matter to window panes. The device is also very practical as a substitute for thumb tacks which are mounted on bulletin boards.

I have found the attachment device of my invention in its various forms extremely practical in its construction, and while I have described certain preferred embodiments of

my invention, I desire it to be understood that modifications may be made and that no limitations upon my invention are intended other than are imposed by the scope of the appended claims.

What I claim as new and desire to secure by Letters Patent of the United States is as follows:

1. A hinged fastening device comprising a tab adapted to engage a flat surface, a resilient clip pivotally mounted on said tab and adapted to carry a sheet-like member in hinged relation to said aforementioned surface, and spring means for maintaining said clip in substantial alignment with said tab. 75

2. A hinged fastening device comprising a sheet-like member, a tab adapted to engage said sheet-like member, a clip pivotally mounted on said tab and arranged to carry a sheet-like member in a position adjacent said aforementioned sheet-like member, and spring means associated with said clip for maintaining said second mentioned sheet-like member substantially parallel with said first mentioned sheet-like member. 85

3. In a hinged fastening device, a gummed tab adapted to engage a substantially flat surface, a pivotally mounted clip carried by said tab and adapted to engage a sheet-like member, and spring means connected to said clip and engaging said tab for maintaining said clip in substantial alignment with said tab with the sheet-like member carried by said clip in substantial adherence with respect to the sheet-like member on which said tab is mounted. 95

4. A hinged fastening device comprising a gummed tab adapted to engage a substantially flat surface, a clip pivotally mounted on said tab, said clip being arranged to engage opposite sides of a sheet-like member for hingedly mounting said sheet-like member with respect to the aforesaid substantially flat surface, and a spring device connected to said clip adjacent the upper extremity thereof and resiliently engaging said tab for maintaining said clip in a plane substantially aligned with the plane of the aforesaid flat surface for mounting said sheet-like member with respect to said surface. 110

5. In a hinged fastening device, a fibrous tab having a gummed surface adapted to engage a flat supporting surface, a resilient clip pivotally mounted on said gummed tab and adapted to secure an envelope in position adjacent said supporting surface, a multiplicity of covers carried by said resilient clip for preventing direct contact between the parts of said clip and said envelope, and a finger grip connected to each of said covers for guiding said covers on or off of the parts of said clip. 120

6. In a hinged fastening device, a gummed tab adapted to engage a substantially flat supporting sheet, a resilient clip pivotally 130

- mounted on said gummed tab, said clip having a pair of spring jaws, means covering each of said jaws for engaging an envelope therebetween for mounting said envelope 5 with respect to said supporting sheet in a position permitting inspection of both sides of said envelope, and a finger grip connected to each of said means for guiding said means on or off of said jaws.
- 10 7. In a hinged fastening device, a paper tab, a spring clip, means extending substantially across a lateral portion of said tab for pivotally supporting said spring clip, said spring clip comprising a pair of spring jaws 15 adapted to engage opposite sides of a flat sheet of material to be supported adjacent said laterally supporting sheet, means interposed between the spring jaws of said clip and said flat sheet of material for presenting 20 a substantially flat gripping surface between the spring jaws of said clip and the sheet of material to be supported therein, and a finger grip extending at an angle from each of said means for guiding said means on or off of 25 said spring jaws. 80
8. A hinged fastening device comprising in combination with a substantially flat supporting sheet, a paper tab having one side thereof gummed for attachment to said supporting sheet, said tab having a central diametrically extending apertured portion, a rod member extending diametrically of said tab and across the central apertured portion thereof, and a pair of spring jaws secured 30 to said rod member and depending therefrom for engaging opposite sides of a sheet of material adapted to be mounted adjacent said substantially flat supporting sheet. 85
9. A hinged fastening device comprising 40 in combination with a flat supporting sheet, a gummed tab adapted to be attached to said supporting sheet, said gummed tab having a central lateral portion perforated to provide a flexible lug, a resilient clip extending 45 through the perforated portion, and a bar extending laterally of said tab and secured to the upper portion of said clip, said flexible lug encircling the upper portion of said clip for maintaining said clip in position for an 50 angular movement through an arc of substantially 180°, said clip including a pair of spring jaws adapted to engage opposite sides of an exhibit sheet for mounting said exhibit sheet in position with respect to said 55 supporting sheet free for lateral movement for inspection of both sides thereof. 100
10. In a hinged fastening device, a paper tab gummed on one side thereof for attachment to a supporting sheet, a resilient clip 60 pivotally mounted on said paper tab, said resilient clip including a pair of spring jaws, flat cover members engageable with each of said jaws, and finger pieces extending from each of said cover members whereby said 65 cover members may be moved into position on 105
- said spring jaws for presenting flat gripping surfaces to an exhibit sheet member for maintaining said exhibit sheet member in predetermined alignment with respect to said supporting sheet and free for inspection on both 70 sides thereof. 110
- In testimony whereof I affix my signature.
